**METHOD FOR TRANSPORTING SULFUR BY
PIPELINE**

Richard L. Every and D'Arcy A. Shock, Ponca City,
Okla., assignors to Continental Oil Company, Ponca
City, Okla., a corporation of Delaware
No Drawing. Filed June 4, 1965, Ser. No. 461,537
10 Claims. (Cl. 302—66)

This invention relates to the pipeline transport of sulfur. More particularly, the invention relates to the transport of sulfur through a pipeline in the form of solid particles suspended in a pumpable slurry.

It has heretofore been proposed to convey sulfur between locations separated by substantial distances by forming the sulfur in small particles, suspending these particles in a carrier liquid to form a pumpable slurry and forcing the slurry through a pipeline linking the two locations. It has also been proposed to form the solid particles in situ in the slurry by initially introducing molten sulfur to the carrier liquid at a temperature above that at which the sulfur freezes, then lowering the temperature of the liquid mixture during agitation thereof to yield a pumpable slurry containing solid particles of the sulfur. Pipeline transport of the sulfur is used to move the sulfur from mining sites where it is brought to the surface by use of the Frasch process, as well as for transhipment from stockpile locations to refineries or treatment plants. Since sulfur occurs naturally in a crystalline form, the slurries previously prepared for pipeline transport have included sulfur particles of this allotropic form.

A problem which has been encountered in the pipeline transport of sulfur slurries is the propensity of the sulfur to precipitate or plate out on the walls of the pipeline, and particularly, upon the internal elements of valves and fittings. This plating out of the sulfur reduces the operating efficiency of the transport, requires increased maintenance of equipment, and contaminates the pipeline to a degree which presents serious problems if it is desired to use the same pipeline for transporting other materials in a relatively high state of purity.

The present invention provides an improved procedure for transporting sulfur through a pipeline in that the extent to which the sulfur is precipitated or plated out in the pipeline during the movement of the sulfur therethrough is substantially reduced. Broadly described, the method of the invention comprises initially converting at least a portion of the sulfur from its usual naturally occurring crystalline allotropic form to its amorphous allotropic form known in the art as sulfur μ , then comminuting or subdividing the sulfur to provide relatively small particles thereof having an average particle size which, in general, do not exceed $\frac{3}{8}$ inch in diameter. The sulfur μ particles are then introduced to a suitable carrier liquid to form a slurry having a sufficiently low viscosity that the material can be pumped through a pipeline without difficulty. The carrier liquid is a liquid in which the sulfur μ particles are insoluble, or at least are not soluble to a degree exceeding 5 weight percent. After formation of the slurry, it can be pumped through a pipeline over substantial distances without the occurrence of sulfur precipitation or plating out to an unacceptably high degree.

In a specific though non-limiting aspect of the invention, the sulfur μ is derived from the reaction of gaseous hydrogen sulfide with liquid sulfur dioxide to yield solid sulfur and water. The hydrogen sulfide can be derived from any convenient source, such as natural gas wells, conversion of elemental sulfur mined by the Frasch process or the like. The solid sulfur which is yielded by the described reaction is, to the extent of at least 50 weight percent, in the amorphous or sulfur μ allotropic form.

2

Because of the high sulfur μ content, the solid sulfur product of the reaction can be pipelined after comminution and slurring without separation of the amorphous sulfur from the crystalline form. Alternatively, if a minimum of precipitation and plating out of the sulfur in the pipeline is sought, the amorphous form can be separated from the crystalline form by carbon disulfide extraction of the crystalline sulfur from the carbon disulfide-insoluble sulfur μ .

The mechanism which is responsible for the lesser tendency of the sulfur μ to be deposited upon surfaces contacted during movement through a pipeline, as compared to the tendency of the crystalline sulfur to be so deposited is not well understood. In any event, we have observed a reduction of well over 50 percent in the amount of sulfur which is precipitated or plated out in the course of pipeline transport of sulfur slurries when the sulfur utilized is in the amorphous form as compared to the crystalline allotropic form. In most instances, the reduction in the amount of sulfur plated and precipitated out in the pipeline is over 80 percent.

From the foregoing description of the invention, it will be apparent that it is an important object of the present invention to provide an improved process for transporting sulfur by pipeline.

A more specific object of the invention is to provide an improved procedure for transporting sulfur containing slurries over substantial distances by pipeline.

An additional object of the present invention is to reduce the maintenance of pipeline equipment which is required in the case of pipelines used for transporting sulfur slurries.

In addition to the foregoing described objects and advantages of the invention, other objects will become apparent from the following detailed description of the invention.

The modus operandi of the present invention is based in our discovery that, for a reason not presently fully understood by us, the amorphous allotropic form of sulfur, termed sulfur μ , is not as readily deposited on solid surfaces encountered in pipeline transport as is the crystalline sulfur, which is by far the predominant allotropic form in naturally occurring sulfur. Over a period of time, the sulfur will revert to the crystalline form, but it will remain in its amorphous form for an adequate period of time for most purposes involving pipeline transport. The reduction in sulfur precipitation occurring in the pipeline varies with the amount of sulfur μ in the total solid sulfur transported so that it is desirable to convert as much of the sulfur to be transported to this allotropic form as is possible. The naturally occurring sulfur generally contains less than about 1 weight percent of the amorphous form of the element.

Any suitable method of converting the crystalline sulfur to the amorphous form can be employed, but we prefer to utilize a process in which the sulfur is initially converted to hydrogen sulfide, then the hydrogen sulfide gas is contacted with liquid sulfur dioxide to yield solid sulfur and ice. The solid sulfur thus produced contains over 50 weight percent of the amorphous sulfur μ and can be easily recovered from the sulfur dioxide an ice preparatory to forming a slurry suitable for shipping the sulfur. The preference for utilizing this method of preparing sulfur μ stems from the ease with which the sulfur can be converted to hydrogen sulfide, the fact that other methods of producing sulfur μ require inputs of large quantities of heat, and the fact that hydrogen sulfide is itself an abundant by-product of the oil and gas industry and thus may provide a significant source of sulfur which it is desirable to ship by the described method. Where crystalline sulfur is available and to be shipped, it can be converted to hydrogen sulfide by contacting the ele-

mental sulfur with hydrogen gas at temperatures less than 310° C. If the sulfur is available in the form of ores, such as metallic sulfides, these can be contacted with a suitable acid to form hydrogen sulfide. The gas can also be prepared by heating mixtures of sulfur, paraffin hydrocarbons and asbestos fibers. In instances where a large supply of sour natural gas is at hand, this material is sufficiently rich in H₂S that it can be passed directly into the liquid sulfur dioxide to provide a substantial quantity of solid sulfur.

The procedure of contacting the H₂S gas with the liquid sulfur dioxide can be carried out at a wide variety of temperatures and pressures, provided the SO₂ is retained in the liquid state and the H₂S in the gaseous state. It is preferred however, to operate at pressures of from about 15 to about 30 p.s.i.a. and at a temperature below about -10° C. The yield of sulfur μ from the reaction decreases as the temperature at which the reaction is carried out is decreased. On the other hand, it is preferred to maintain the temperature and pressure in the reaction zone at levels such that the water produced by the reaction occurs as ice. This prevents hydration of the liquid SO₂, reduces corrosion problems, and simplifies the separation of the reaction products from the sulfur dioxide. In view of these considerations bearing upon the temperature range employed, it is preferred to utilize a reaction zone temperature which is in the range of from about -60° C. to about -10° C. at pressures of from about 15 p.s.i.a. to about 30 p.s.i.a. It should be pointed out, however, that where immediate pipelining of the sulfur is in prospect, it may be desirable to carry out the reaction at considerably higher pressures, and in these cases the temperatures used will be adjusted to maintain the SO₂ in the liquid phase and the H₂S in the gaseous phase. Details of the procedure for contacting the gaseous H₂S with liquid SO₂ are set forth in co-pending application for U.S. Letters Patent Ser. No. 422,257, filed Dec. 30, 1964, and assigned to the assignee of this application.

Upon completion of the reaction, little difficulty is experienced in separating the solid products, sulfur and ice, from the liquid SO₂, and, if desired, the ice may then be melted and the solid sulfur easily separated from the resulting water in which it is insoluble, and finally dried. If it is desired to ship only the portion of the solid sulfur product which is in the amorphous allotropic form, and which will therefore precipitate and plate out in the pipeline to the minimum extent, the sulfur μ can be isolated from the crystalline sulfur by selective extraction of the latter material with carbon disulfide in which the amorphous sulfur is insoluble. In general, however, it is preferred neither to dry nor separate the sulfur μ .

TABLE I

Carrier Liquid	Sulfur Source	Tempera-ture of Slurry, ° C.	S-Liquid Ratio, gms./ml.	Duration of Run, hours	Plating on Tube, grams of S	Comments

¹ The sour condensate carrier liquid had the following composition-component and weight percent: Propane, 0.2; iso-butane, 1.0; normal butane, 2.8; iso-pentane, 3.6; normal pentane, 3.3; hexanes and heavier 89.1.

prior to grinding and introduction into the pipeline charge.

The sulfur is moved through the pipeline as a slurry. To form the slurry, the sulfur, preferably including at least 1 weight percent, and most preferably at least 50 weight percent, of the amorphous form of the element, is initially comminuted or subdivided to form relatively small particles which preferably do not exceed $\frac{3}{8}$ inch in diameter. It is most preferred that the particles do not exceed $\frac{1}{4}$ inch in average diameter. Any suitable grinding or comminution procedure can be used to effect the particle size reduction.

The type of liquid carrier employed is not particularly critical, but should be a non-solvent for the element sulfur, or at least dissolve the sulfur to no greater extent than 5 percent by weight. The slurry form of transport has the advantage of permitting two materials to be moved through the pipeline simultaneously and it is, of course, desirable to use as the carrier liquid, a liquid which is in supply in the locale of the origination of the sulfur shipment, and/or is in demand at the destination. Since petroleum derivatives are frequently available near sulfur deposits, particularly in the United States, preferred carrier materials include, but are not limited to, such petroleum derived liquids as crude oils, crude oil condensates, various crude oil distillates, kerosene and benzene.

The only significant limit on the viscosity of the slurry used for transporting the sulfur is that it be sufficiently low to be pumpable. It is preferably, however, to assure ease of movement through the pipeline, that the horsepower requirements to pump the slurry through the pipeline not exceed 1.8 times the horsepower requirement to move the pure liquid carrier through the pipeline.

The invention can be better understood by referring to 35 the following examples of its practice.

Example 1

In laboratory tests, solid sulfur prepared by the H₂S-SO₂ method hereinbefore described was slurried in 40 various carrier liquids. The slurries were then placed in a glass beaker and maintained at a constant temperature of about 54° C. with stirring. A stainless steel tube was immersed in the slurry and water was circulated in the tube to maintain its temperature at about 23° C. After 45 a period of 24 hours, the sulfur which had precipitated on the cold tube was collected, dried and weighed.

In preparing the solid sulfur by the reaction of gaseous H₂S with liquid SO₂, the SO₂ was maintained at a temperature of between -10° C. and -35° C. In some of 50 the sulfur preparations, pure hydrogen sulfide gas was utilized; in others, sour natural gas containing a high percentage of hydrogen sulfide gas was employed. In all

² In these runs the H₂S was derived from sour natural gas which was passed directly into the liquid SO₂.

cases, the solid sulfur resulting from the H_2S - SO_2 reaction contained from 50 to 60 weight percent of the amorphous or sulfur μ allotropic form of the element.

For purposes of comparison, slurries of commercially available "Flowers of Sulfur" in the same carrier liquids were subjected to the same plating or precipitation tests. Flowers of Sulfur consists almost entirely of the crystalline form of the element and thus simulates closely the form in which elemental sulfur has heretofore been transported as a slurry through pipelines.

The results obtained in all runs are set forth in Table I.

The data set forth in Table I clearly indicate that the solid sulfur containing a high percentage of sulfur μ plates out to a much lesser extent than the crystalline Flowers of Sulfur. The data also indicates that some further reduction in precipitation occurs when the sulfur is moistened with water prior to formation of the hydrocarbon carrier slurries. In the case of the sulfur formed from the H_2S - SO_2 reaction, some moisture formed in the reaction is occluded in the sulfur and unless it is removed by drying, remains therein as the slurry is formed. The mechanism by which the moisture further retards precipitation is not known.

Example 2

A slurry comprising 50 parts by weight sulfur μ and 40 parts by weight kerosene is pumped through an eight inch pipe-line over a distance of 150 miles using an 8 stage centrifugal pump driven by a 1,000 horsepower electric motor. Upon completion of the pipeline transport, the pipeline is thoroughly cleaned internally and then a second slurry containing 5 parts by weight of crystalline sulfur and 40 parts by weight kerosene is pumped therethrough, using the same pump and at the same rate.

The total sulfur content of the slurries arriving at the pipeline destination is then recovered from the kerosene. By this method, it is determined by difference that about 2 weight percent of the sulfur μ is left in the pipeline as a result of plating and precipitation, whereas about 20 weight percent of the crystalline sulfur precipitates in the pipeline.

From the foregoing description of the invention, it will have become apparent that an improved method for transporting sulfur by pipeline is provided. Lower sulfur losses in the pipeline result from the use of the method, and in addition, pipeline maintenance is decreased.

Although certain specific embodiments of the invention have been described as exemplary of its practice, these examples are not intended to limit the invention in any way, or to constitute any definition of its true scope. Other process parameters and materials may be used in accordance with the broad principles outlined herein, and when so used, are deemed to be circumscribed by the spirit and scope of the invention except as necessarily limited by the appended claims or reasonable equivalents thereof.

What is claimed is:

1. A method of transporting sulfur comprising:
  - (a) forming a pumpable slurry of solid particles of sulfur, wherein an amount effective to reduce precipitation and adherence to the interior parts of a transporting vessel is in the sulfur μ amorphous allotropic form; and
  - (b) pumping said slurry through a pipeline.
2. A method of transporting sulfur comprising:
  - (a) converting an amount of the sulfur to the sulfur μ amorphous allotropic form; said amount being

effective to reduce precipitation and adherence to the interior parts of a transporting vessel;

(b) comminuting the sulfur to provide solid particles thereof;

(c) forming a pumpable slurry of the solid particles of sulfur in a carrier liquid; and

(d) pumping the slurry through a pipeline to the location to which the sulfur is to be transported.

3. A method of transporting sulfur as defined in claim

2 wherein at least 50 weight percent of the sulfur to be transported is converted to the sulfur μ amorphous allotropic form.

4. A method of transporting sulfur as defined in claim 2 wherein the average size of said particles does not exceed $\frac{3}{8}$ inch in diameter.

5. The method of transporting sulfur defined in claim 2 wherein said carrier liquid is selected from the group consisting of sour crude oil condensate, kerosene and benzene.

6. The method of transporting sulfur as defined in claim 2 wherein the amount of sulfur slurried with said carrier liquid imparts a viscosity to said slurry such that the horsepower requirement to pump said slurry through said pipeline does not exceed 1.8 times the horsepower requirement to pump said carrier liquid alone through said pipeline.

7. The method of transporting sulfur defined in claim 2 wherein said converted portion of the sulfur is converted by

(a) converting a portion of the sulfur to hydrogen sulfide;

(b) contacting the hydrogen sulfide in a gaseous state with liquid sulfur dioxide; and

(c) recovering as a reaction product of said contact, solid sulfur containing at least 50 weight percent sulfur μ .

8. The method of transporting sulfur defined in claim 7 wherein the hydrogen sulfide is contacted with the liquid sulfur dioxide at a temperature of from about -60° C. to about -10° C.

9. The method of transporting sulfur defined in claim 7 wherein sulfur μ in said reaction product is recovered by selectively extracting the crystalline sulfur therefrom with carbon disulfide.

10. The method of transporting the sulfur content of sour natural gas from a source of the gas to a remote location comprising:

contacting the sour natural gas with liquid sulfur dioxide to yield water and solid sulfur with an amount of the sulfur in the sulfur μ amorphous allotropic form; said amount being effective to reduce precipitation and adherence to the interior parts of a transporting vessel;

recovering the solid sulfur from the environment of said contact;

forming a pumpable slurry of the solid sulfur in a carrier liquid; and

pumping the slurry through a pipeline to the location to which the sulfur is to be transported.
